THERMO FOGGING UNIT

Richard H. Avant, Rochester, N.Y., assignor to Bernz-O-Matic Corporation, Rochester, N.Y.

Filed Apr. 2, 1973, Ser. No. 347,282

Term of patent 14 years

Int. Cl. D23—01

U.S. Cl. D23—18

FIG. 1.

FIG. 2.

FIG. 1 is a perspective view of a thermo fogging unit showing my new design;

FIG. 2 is an elevational view taken from the side opposite that shown in FIG. 1;

FIG. 3 is a top plan view thereof;

FIG. 4 is a front elevational view thereof; and

FIG. 5 is a rear elevational view thereof.

It is to be understood that the openings are continuous throughout the area indicated in FIGS. 1, 2 and 3.

I claim:

The ornamental design for a thermo fogging unit, as shown and described.
